COMBINED CHAIR AND TABLE

Robert S. Wilson, Tucson, Ariz.

Application March 28, 1955, Serial No. 35,247

Term of patent 7 years

(Ct. D15—1)

Fig. 1 is a front perspective view of a combined chair and table showing my new design;

Fig. 2 is a rear perspective view thereof with the table element in position for use; and

Fig. 3 is a front elevational view of the combined chair and table as shown in Fig. 2.

I claim:

The ornamental design for a combined chair and table, as shown.
